PUMP

Cyriel Roose and Thomas E. Jackson, Detroit,
Mich., assignors to Sherman, Jackson & Roose
Company, Detroit, Mich., a corporation of
Michigan

Application May 15, 1942, Serial No. 443,038

2 Claims. (Cl. 103—178)

This invention relates to pumps and has particular reference to an inexpensive and simple type of hand operated pump which is particularly adapted for pumping water or other liquids.

A principal object of the invention is to provide a hand operated pump in which many of the parts thereof are made of a non-metallic material such, for example, as wood.

Another object of the invention is to provide an inexpensive type of hand operated pump which is particularly adapted for use in connection with a bucket or pail of water for pumping such water through a nozzle under sufficient pressure to throw a fairly continuous stream of water in the neighborhood of at least twenty feet to twenty-five feet.

Another object of the invention is to provide an inexpensive and simple type of pump which is adapted for use as home firefighting equipment or for use in pumping or spraying liquids such as insecticides and which pump is constructed and arranged, during operation thereof, to discharge a continuous stream of liquid.

Another object of the invention is to provide a pump in which the cylinder thereof is formed by a block of non-metallic material, such as wood, which is impregnated with oil or other suitable material so as to resist deterioration by the liquids handled by the pump.

Other objects and advantages of the invention will be apparent from the consideration of the following specification taken in conjunction with the accompanying drawing of which there is one sheet and wherein:

Fig. 1 is a sectional view of a bucket having a pump employing the invention arranged therein and adapted for pumping liquid from the bucket through a conduit or pipe which is connected to the discharge of the pump;

Fig. 2 is an enlarged elevational view of the pump embodying the invention, parts thereof being broken away and others shown in section for illustrating details of the construction of the pump; and

Fig. 3 is a horizontal sectional view taken in a plane along the line 3—3 of Fig. 2 looking in the direction of the arrows.

A pump embodying the invention is particularly adapted, although not limited, for use in pumping liquid, such as water, and when assembled with a bucket as illustrated in Fig. 1 is particularly adapted for use as a piece of home fire fighting equipment for fighting incendiary bombs, etc., or for use as a garden spray for dispersing insecticides, etc. The assembly illustrated in Fig. 1

comprises a bucket 10 having a handle 12 and a pump indicated generally at 14 secured within the bucket 10 by means such as a pair of straps 16 encircling the body of the pump and suitably fastened to the side of the bucket 10. The bucket 10 may be provided with foot rests 18 for holding the bucket in position during such time as the pump is operated. The pump 14 is adapted to pump liquids from the interior of the bucket 10 and to discharge such liquid through a pipe indicated generally at 20 which is connected to the discharge outlet 22 of the pump.

As illustrated more particularly in Fig. 2, the pump comprises a body member 24, a handle 26, a piston 28, an inlet 30 and the discharge or outlet 22. The body member 24 as illustrated comprises a block of non-metallic material, such as wood, which is formed internally therein to provide a cylinder bore 32. The bore 32 may be formed by drilling a cylindrical hole through the body member 24. Cypress wood impregnated with oil may be employed for making the body member 24. The cylinder bore 32 is closed at its lower end by a disc-like body 34 which is formed with an opening therein, such opening providing the inlet 30 to the pump cylinder. The body 34 may be formed to include a projection 36 which seats within the end of the cylinder 32 for locating the member 34 with respect to the body member 24 and such projection 36 is formed to provide a seat 38 for a valve member 40, the seat 38 and valve member 40 comprising an inlet valve for the pump. The valve member 40 may comprise a spherical ball of any suitable material and is adapted to rest upon the seat 38 for the purpose of closing the inlet 30 to the pump cylinder or bore 32. Means, such as a pair of nails 42 carried by the body member 24 a short distance above the valve seat 38, are provided to form a stop for limiting the upward travel of the valve member 40, the upper position of which is indicated in dotted lines.

The piston 28 of the pump, as illustrated, comprises a hollow tubular member 44 having an outside diameter materially less than that of the inside diameter of the cylinder bore 32. The piston includes a head comprising a member 46 provided with an annular flange 48 which is threadedly or otherwise suitably secured to one end of the tubular member 44 and clamps an annular gasket 50 against a washer 52 which is held against the end of the tubular member 44. A valve member comprising a spherical ball 56 is arranged within the tubular member 44 and is adapted to cooperate with spaced valve seats 58.

and 60. The valve seat 58 may be provided by the upper circular inside edge of the member 46 while the other valve seat may be provided by an annular ridge formed in the wall of the tubular member 44. The tubular member at its upper end is suitably connected to the handle 26 in order that the piston may be manually or otherwise reciprocated in the cylinder bore 32. The upper end of the cylinder bore is closed by a disc member 62 which is provided with an opening for the tubular member 44. A washer 66 may be arranged on a seat at the upper end of the cylinder bore and provide an upper bearing or guide for the tubular member 44 and suitable packing may be provided between the washer 66 and the disc member 62. The disc member 62 may be secured to the body member 24 by means of one or more screws 68. A sleeve-like member 70 disposed around the tubular member 44 at the upper end thereof and adjacent to the handle 26 is adapted to contact the outside surface of the disc member 62 for limiting the downward movement of the piston. The discharge from the pump comprises a nipple secured in a laterally extending opening formed in the side wall of the body member, the inner end of the nipple communicating with the upper end of the cylinder bore 32. Between the upper and lower positions of the valve member 56 the tubular member is provided with a plurality of openings 72, which together with the valve member 56 and valve seat 58 forms a by-pass for transferring liquid in the cylinder from the inlet side of the cylinder to the discharge side thereof.

The pump may be supported by a plurality of legs 76 which together with the disc 34 are secured to the body member 24 by means of one or more screws such as 80, and a screen 18 may be wrapped around the legs 76 so as to provide a filter for screening the liquid drawn into the pump from the bucket 10.

Upon upward movement of the piston 28 the valve 56 will seat and the valve 40 will unseat thereby drawing fluid into the pump cylinder below the piston head and through the inlet opening 30. When the head reaches the upward limit of its travel in the cylinder 32 just below the discharge 22, a stop 51 carried by the rod 44 will engage the washer 66 at the upper end of the cylinder and as the inflow of liquid to the pump cylinder ceases the valve 40 will seat on its seat 38 and close the inlet opening, thereby preventing the escape of fluid from the cylinder 32 therethrough. When the piston is at the upper limit of its travel, as previously indicated, the cylinder 32 will be full of liquid assuming that there was a sufficient supply in the bucket 10. Downward movement of the piston will open the by-pass therethrough by unseating the valve 56 from its seat 58 and under the influence of the liquid passing through the member 46, the valve member 56 will seat on its upper seat 60 while liquid in the cylinder bore 32 will flow through the by-pass in the piston including the openings 72 and be transferred to the discharge side of the piston.

The mass of the piston head and the rod 44 is such that upon movement of the piston from its upper limit of travel to its lower limit of travel, approximately half of the fluid in the cylinder will be forced out through the outlet 22 and hose 20. When the piston reaches the lower limit of its travel, the space in the cylinder 32 on the discharge side of the piston will be occupied by liquid which will be discharged through the outlet 22 on the next upward stroke of the piston.

the valve 56 during such upward stroke seating on its seat 58 as previously indicated.

The interior of the tube 44 during the upward stroke of the piston is open through the opening 72 to the cylinder, and while the interior of this tube might be permanently closed at 60 if desired, it is here shown as being open except at the top thereof where it is closed by a plug to which the handle 26 is secured. The space in the tube 44 above the valve seat 60 will function as an air bell or expansion chamber if it is filled with air. It might, of course, have the air removed therefrom if the pump is filled with a liquid in an inverted position.

15 From the foregoing it will be evident that the pump is constructed and arranged to discharge liquid on both the up and down strokes of the piston. The provision of a suitable nozzle on the end of the hose 20 will enable the liquid discharged from the pump to be forced in a stream or sprayed, and the continuous operation of the piston will discharge a continuous stream of liquid through the hose 20. A pump of this type in view of its simplicity and economy in manufacture is particularly adapted for use as a piece of home fire fighting equipment for use in dealing with incendiary bombs, etc., and in addition may be used as a garden spray for dispersing water, insecticides, etc. When the bucket is full of water 20 the pump is ready for instant use, and as the bucket may be refilled during operation of the pump, no interruption in the discharge of water through the hose 20 is necessary during such time as the pump and its assembly with the bucket 35 might be used in fighting fires.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

We claim:

- 45 1. A portable liquid pump comprising a cylinder having a valve controlled inlet at one end thereof and a discharge outlet at the other end thereof, a piston reciprocable in said cylinder and comprising a head, a rod connected to said head for reciprocating the same in said cylinder and projecting from the discharge end of said cylinder, said head upon movement thereof away from said valve controlled inlet operating to draw liquid into said cylinder on the intake side thereof and to discharge liquid from said cylinder on the discharge side thereof, said rod comprising a hollow tubular member and said head comprising an annular member secured to the end of said tubular member and projecting therein so as to define a valve seat therein, said tubular member having an opening in the wall thereof spaced from said valve seat and a ball valve member in said tubular member and cooperable with said valve seat, said valve seat and member comprising a 55 valve controlled opening in said head which opens upon movement of said head toward said cylinder inlet so as to permit liquid in said cylinder to bypass said piston head, said tubular member being formed to provide a valve seat above said opening, said ball valve member being adapted to seat on said last-mentioned valve seat during downward movement of said piston head so as to prevent the entrance of liquid into said hollow member above said last-mentioned valve seat, said 60 rod and head having such mass that during move- 70

ment thereof in the cylinder toward the inlet thereof liquid will be displaced from the cylinder through the outlet thereof.

2. A liquid pump comprising a cylinder having a valve controlled inlet at one end thereof and a discharge outlet at the other end thereof, a piston reciprocable in said cylinder and comprising a head, a rod connected to said head for reciprocating the same in said cylinder and projecting from the discharge end of said cylinder, said head upon movement thereof away from said valve controlled inlet operating to draw liquid into said cylinder on the intake side thereof and to discharge liquid from said cylinder on the discharge side thereof, said rod comprising a hollow tubular member and said head comprising an annular member secured to the end of said tubular member and defining a valve seat therein, said tubu-

lar member having an opening in the wall thereof spaced from said valve seat and a valve member in said tubular member and cooperable with said valve seat, said valve seat and member comprising a valve controlled opening in said head which opens upon movement of said head toward said cylinder inlet so as to permit liquid in said cylinder to by-pass said piston head, said tubular member being provided with a second valve seat upon which said valve member seats upon movement of said head towards the inlet of said cylinder, said rod and head having such mass that during movement thereof in the cylinder toward the inlet thereof liquid will be forced from the cylinder through the outlet thereof.
